UNITED STATES PATENT OFFICE.

EUGENE BARKER, OF BATAVIA, NEW YORK.

CLAMP-BAR.

No. 874,725.

Specification of Letters Patent.

Patented Dec. 24, 1907.

Application filed April 16, 1907. Serial No. 368,525.

To all whom it may concern:

Be it known that I, EUGENE BARKER, a citizen of the United States, residing at Batavia, in the county of Genesee and State of New York, have invented new and useful Clamp-Bars, (Case D,) of which the following is a specification.

This invention relates to bars for gluing clamps and its object is to provide a device of this character made up of wood and metal combined in such a manner as to present all of the advantages of a wooden bar with the strength and rigidity of a metal bar.

Bars of this character as heretofore constructed have been made either of wood or metal. Wooden bars are desirable because of their cheapness and lightness but are undesirable because they can not stand the strains to which metal bars may be subjected and do not hold the jaws of the clamp as positively as the metal bars. Metal bars however, are objectionable because of their weight and cost. The object of the present invention is, as before stated, to combine the advantages of the two forms of bars by forming the body portion of wood and reinforcing the same with a metallic core while the working faces of this bar are similarly reinforced.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a perspective view of a portion of a bar constructed in accordance with the present invention; Fig. 2 is a longitudinal section therethrough; Fig. 3 is a transverse section through the bar; and Fig. 4 is a longitudinal section through a portion of a modified form of bar.

Referring to the figures by characters of reference, 1 designates a metallic core consisting of a metal strip disposed to extend throughout the length of the bar and corrugated transversely. Fitting snugly against opposite faces of this core are wooden bars 2 constituting the body of the device and these bars are grooved longitudinally as shown at 3, said grooves registering to form a channel 4. The core 1 extends to the inner wall of this channel and its opposite edge is flush with those faces of the bars 2 opposite the channel 4.

A back plate 5 preferably formed of sheet metal extends throughout the length and breadth of the device and has longitudinal flanges 6 which lap the sides of the bar members 2 and are fastened thereto by means of bolts or rivets 7 which extend transversely through the members 2 and the core 1. Extending throughout the length and breadth of the front face of the bar is a plate 8 preferably formed of sheet metal and having longitudinal flanges 9 which lap the sides of the bar and are secured thereto by bolts or rivets 10 extending transversely through the members 2 and core 1. A longitudinal series of 70 transversely extending corrugations 11 is formed along the center of plate 8 and said corrugations fit snugly within the channel 4 and against the core and constitute a rack 1. These corrugations may be formed either by 75 stamping the plate 8 or by passing the same between corrugated rollers.

It is of course to be understood that the corrugations 11 constitute teeth designed to be engaged by a jaw of a clamp and as the 80 pressure exerted by the jaw is directed in the direction of the width of core 1 it is apparent that said core will maintain the bar perfectly rigid at all times and prevent it from bending. This result is obtained particularly in 85 view of the fact that the core is corrugated in the direction of its width, or the line of pressure thereagainst, and in view also of the fact that the members 2 fit snugly within the corrugations. It is apparent that the plates 90 5 and 8 take up all the wear resulting from the adjustment and binding action of the jaw or jaws, and therefor the members 2 merely act as reinforces for the core and constitute backings for the plates 5 and 8. In view of 95 the fact that the two plates 5 and 8 and the core constitute the only metal used in the construction of the bar and as these plates and core are comparatively light it will be understood that the bar will weigh very little 100 more than one constructed entirely of wood. However, as the metal is placed only where it can be best used for reinforcing and strengthening the bar it will be seen that said bar possesses practically the same strength 105 and all the other advantages of an all-metal bar.

In long bars, and bars which are to be subjected to more than the ordinary pressure, the core can be doubled as shown in Fig. 4 110 by utilizing two oppositely disposed metal strips 12 which are transversely corrugated.

Various other changes in the details of construction and in the arrangements of the parts can also be made without departing from the present invention.

5. What is claimed is:

1. A clamp bar comprising a metallic core, members secured upon opposite faces thereof, and a rack interposed between said members and contacting with one edge of the 10 core.

2. A clamp bar comprising a metallic core, members secured upon opposite faces of the core, a back plate secured upon the members and contacting with one edge of the core, and 15 a rack secured to said members and contacting with the opposite edge of the core.

3. A clamp bar comprising a metal core, members secured upon opposite faces thereof, and a plate secured upon said members 20 and having a longitudinal series of transverse corrugations projecting between said members.

4. A clamp bar comprising a transversely corrugated metal core, oppositely disposed 25 members fitting snugly against opposite faces of the core, and plates embracing and secured upon opposite faces of said members, one of said plates having a longitudinal series of transverse corrugations.

30 5. A clamp bar comprising a transversely corrugated metal core, members clamped upon opposite faces of said core, and plates secured upon the members along opposite

edges of the core, one of said plates having a longitudinal series of transverse corruga- 35 tions.

6. A clamp bar comprising a metal core, members secured upon opposite faces of the core, and plates secured upon the members and along opposite edges of the core. 40

7. A clamp bar comprising a transversely corrugated metal core, members secured upon opposite faces thereof, said members having registering grooves in one face constituting a channel, a back plate embracing the 45 members and disposed along one edge of the core, and a plate embracing the members and having a longitudinal series of transverse corrugations disposed along the other edge of the core. 50

8. A clamp bar comprising a metallic core, members secured upon opposite faces thereof, and a rack secured to the members and contacting with one edge of the core throughout the length thereof. 55

9. A clamp bar comprising oppositely disposed corrugated metallic strips constituting a core, and members secured upon opposite faces of the core.

In testimony that I claim the foregoing as 60 my own, I have hereunto affixed my signature in the presence of two witnesses.

EUGENE BARKER.
